UNITED STATES PATENT OFFICE.

GEORGE A. KEENE, OF LYNN, MASSACHUSETTS, ASSIGNOR TO HIMSELF AND SETH D. WOODBURY, OF SAME PLACE.

COMBINED BED AND CHAIR.

Specification of Letters Patent No. 29,038, dated July 3, 1860.

To all whom it may concern:

Be it known that I, GEORGE A. KEENE, of Lynn, in the county of Essex and Commonwealth of Massachusetts, have invented 5 a new and useful Reclining Chair and Extension-Bed Combined; and I do hereby declare that the following is a full, clear, and exact description of the construction and operation of the same, reference being had 10 to the accompanying drawings, forming a part of this specification, in which—

Figure 1 is a perspective view, showing the extension drawn out so as to be used as a couch or bed; Fig. 2, a similar view of the 15 same with the extension, when used as a reclining chair for invalids or watchers; and Fig. 3 is a top view with the extension pushed under so that the whole shall occupy no more area than the bed itself. The bottom slats are not represented.

Like parts are indicated by the same letters in all the figures.

To enable others skilled in the art to make and use my invention, I will now 25 describe its construction and operation.

The nature of my improvement consists in the use of a frame, or suitably upholstered extension, arranged in such a manner as to slide under, and from, the bed on one side of 30 the same, so that it may be used to move an invalid on, when the bed is to be made, or for a watcher, a child, or whenever occasion requires a wider bed; and second, so constructing said extension as to operate 35 either as a bed and couch or a reclining chair, substantially as hereinafter described; and third, the combination and arrangement, in one article of furniture, of a "cabinet chair," reclining-chair, and extension bed or 40 couch.

The bedstead, A, is constructed like those in common use, except that the connecting bars, at the head and foot, are a little deeper.

B is a frame just long enough to slide in 45 between the posts, as shown in the drawings, and supported by means of cleats attached to the lower edge of the inner sides of the bars, at the head and foot of the bedstead.

B' is an arm, or continuation, of the frame, B, to support the back of the chair, 50 D, when in a horizontal position, as represented in Fig. 1.

C is the seat of the chair which is made fast to the side of the frame, B, near its center, as seen in Fig. 2. This seat, as also 55 the frame, B, when drawn out, is supported by the legs, I.

D is the back piece hinged at d d to the seat, C.

E is the leg-rest hinged at i i to the front 60 of the seat.

e is a foot-rest, or foot-board, hinged so as to drop down when required, as shown in Fig. 1.

The parts, C, D and E, may, of course, be 65 upholstered in any suitable manner.

F is a flat piece of iron, the lower end of which is pivoted to the leg-rest, E, as shown in Figs. 1 and 2; it is also slotted near the center and at the upper end, so that pins or 70 screws, f and g, may pass through it into seat, C, and back, D. Thus it is evident that the back, D, and rest, E, may have any desired degree of inclination from a perpendicular to a horizontal, and be held in place 75 by tightening either of the screws, f, or g, so that it will not slide in the slot.

b is a button attached to the under side of the frame, B, to hold up the leg-rest, E, when the latter is in a horizontal position. 80

G is a box for holding a chamber vessel, h, being a hinged cover.

Thus we have several very useful and convenient articles of furniture combined.

What I claim as my invention and desire 85 to secure by Letters Patent, is—

The combination and arrangement of a bedstead, extension bed, or couch, and chair, substantially as specified.

GEORGE A. KEENE.
